[57] **ABSTRACT**

A floating roof tank is provided having a fixed vertical pole disposed through an opening in the floating roof. The vertical pole serves as both a gauging pole and an anti-rotational pole. The gauging pole is perforated to allow the

free flow of liquid into and out of the gauging pole. A float is disposed within the gauging pole. The float has a pair of spaced-apart seals which effectively prevent the escape of vapor from within the tank through the gauging pole. Other seals effectively prevent the escape of vapor from within the tank around the periphery of the gauging pole and around the periphery of the roof itself. The gauging pole, in combination with the double sealed float, provides the operator of the tank with the ability to sample the tank from the top of the gauging pole, rather than having to stand on the floating roof itself.

1 Claim, 3 Drawing Sheets

A statutory invention registration is not a patent. It has the defensive attributes of a patent but does not have the enforceable attributes of a patent. No article or advertisement or the like may use the term patent, or any term suggestive of a patent, when referring to a statutory invention registration. For more specific information on the rights associated with a statutory invention registration see 35 U.S.C. 157.

1

FLOATING ROOF TANK WITH SEALED
GAUGING POLE

BACKGROUND

Floating roof tanks are common in the petroleum and chemical processing industries to store volatile liquids. In floating roof tanks, the roof is generally adapted with pontoons so that the roof floats on the surface of the liquid. Seals are typically provided at the peripheral edges of the roof to seal the roof as it floats up and down with the liquid level, thereby preventing the escape of vapors from the tank.

In floating roof tanks, it is typically necessary to provide an opening to allow operators to extract samples of the liquid from the tank. However, using such openings to extract samples requires the operator to physically stand upon the roof of the tank. In many cases, this is somewhat dangerous, such as where the tank may emit toxic vapors. This is especially a problem when the liquid level in the tank is low so that the roof of the tank is well-below the top of the tank's side walls. In such cases, the roof and the tank's side walls form a semi-enclosed space wherein vapors are not readily dispersed in the wind.

Accordingly, there is a need for a floating roof tank which can be sampled without having to stand on the tank roof.

SUMMARY

The invention satisfies this need. The invention is a floating roof comprising (a) a bottom wall; (b) substantially vertical side walls attached to the bottom wall, the side walls defining a top opening; (c) a roof disposed within the side walls, the roof having a central portion, peripheral edges and a gauging opening and being shaped and dimensioned to substantially conform to the top opening, the roof being adapted to float on liquid disposed within the tank and having seals disposed at the peripheral edges to substantially seal vapor within the tank; (d) a hollow gauging pole disposed vertically within the tank and protruding through the gauging opening in the roof, the gauging pole having side walls with an exterior side and an interior side, the gauging pole side walls being perforated to allow liquid within the tank to flow into the gauging pole and having external seals adapted to seal the exterior side of the gauging pole side walls to the tank roof so as to prevent vapor within the tank from escaping through the gauging opening on the exterior side of the gauging pole side walls; and (e) an internal float disposed within the gauging pole adapted to float on liquid disposed within the tank, the float having a pair of spaced apart wiper seals adapted to seal the float to the interior side of the gauging pole side walls so as to prevent the escape of vapor from the tank along the interior side of the gauging pole side walls.

The invention allows operations personnel to sample the floating roof tank of the invention without having to stand upon the floating roof. Operations personnel merely remove the internal float within the gauging pole and sample the tank through the gauging pole. The gauging pole doubles as an anti-rotational pole which prevents the rotation of the floating roof relative to the sides of the tank.

DRAWINGS

These features, aspects and advantages of the present invention will become better understood with regard to the following description, appended claims and accompanying figures where:

FIG. 1 is a side view of a floating roof tank of the invention;

2

FIG. 2 is a cross-sectional view of the floating roof tank of FIG. 1 taken along line 2—2;

FIG. 3 is a cross-sectional side view showing in detail the gauging pole as it protrudes through the roof of a floating roof tank;

FIG. 4 is a cross-sectional side view of an internal float disposed within a gauging pole useful in the invention; and

FIG. 5 is a top view of a gauging opening in the roof of a floating roof tank of the invention, showing a gauging pole disposed therein.

DESCRIPTION OF THE INVENTION

The following discussion describes in detail one embodiment of the invention and several variations of that embodiment. This discussion should not be construed, however, as limiting the invention to those particular embodiments. Practitioners skilled in the art will recognize numerous other embodiments as well.

The invention is a floating roof tank 10 comprising a bottom wall 12, substantially vertical side walls 14 and a floating roof 16. A hollow gauging pole 18 is disposed vertically within the tank 10 in such a way that it protrudes through a gauging opening 20 defined within the floating roof 16. Disposed within the gauging pole 18 is an internal float 22 which is adapted as described below to alternatively seal the gauging pole 18 and to allow access to the liquid within the tank 10 for sampling purposes.

In a typical embodiment, the hollow gauging pole 18 is a section of pipe, for example, a section of 8-inch, schedule 40 carbon steel pipe. The size and the material of the gauging pole 18 is not critical, however. Other sizes and other materials can be used depending upon the size of the tank 10 and other circumstances.

The gauging pole 18 is perforated to allow liquid within the tank 10 to freely flow into and out of the gauging pole 18. Preferably, the gauging pole 18 is perforated along its entire operative length. This allows for adequate cross-flow of liquids into and out of the gauging pole 18, so that the liquid contents within the gauging pole 18 is representative of the liquid within the tank 10 as a whole. Where the gauging pole 18 is a section of 8-inch, schedule 40 pipe, the gauging pole 18 can be perforated with two rows of one and one eighth inch diameter holes 24 spaced apart by about 18 inches. In a preferred embodiment, the rows of holes 24 are disposed on opposite sides of the gauging pole 18 and the holes 24 of one row are staggered with respect to the holes 24 in the opposite row, as shown in FIG. 1.

In a typical installation, such as that which is shown in FIG. 1, the gauging pole 18 is attached by lateral braces 26 to the side walls 14 of the tank 10 and by vertical braces 28 to the bottom wall 12 of the tank 10.

Optionally, the gauging pole 18 can further comprise a top cap 30.

As also shown in FIG. 1, and in more detail in FIGS. 3 and 5, the guide pole 18 is sufficiently long so as to protrude through the gauging opening 20 in the tank roof 16 when the tank roof 16 is at its maximum height. FIG. 3 illustrates a typical method of protruding the gauging pole 18 through the gauging opening 20. The tank roof 16 is shown to comprise a center section 32 and a periphery 34. At the periphery 34 are provided pontoons 36 for causing the roof 16 to float on liquid within the tank 10. As shown in FIG. 3, the liquid level is designated by the number 38. At the periphery 34, the roof 16 has flexible periphery seals 40 which are adapted to contact the side walls 14 of the tank 10

with sufficient force so as to effectively prevent vapors within the tank **10** from escaping at the periphery **34** of the roof **16**.

At the gauging opening **20**, a gauging opening cylinder **42** can be attached to the roof **16**. The gauging opening cylinder **42** can be cylindrical in shape, but this is not critical. Rollers **44** or similar equipment can be attached proximate to the gauging opening cylinder **42** on opposite sides of the gauging pole **18** so as to allow the roof **16** to smoothly move up and down the exterior of the gauging pole **18**. Gauging pole seals **46** are attached either to the gauging pole **18** or to the tank roof **16** at the gauging opening **20**. As shown in FIG. 3, the gauging pole seals **46** can be sandwiched between two metal plates **47** which form a top flange **49** on the gauge opening cylinder **42**. The gauging pole seals **46** are flexible sheets of material adapted to impinge upon the exterior walls of the gauging pole **18** with sufficient force so as to prevent the escape of vapor within the tank through the gauging opening **20** on the external side of the gauging pole **18**.

As shown on FIGS. 3 and 4, the internal float **22** is disposed within the gauging pole **18**. The internal float **22** is adapted to float on liquid disposed within the tank **10**. The float **22** is typically made from stainless steel, but other materials can be used as well.

As shown in FIG. 4, the float **22** includes a pair of spaced-apart float seals **48** which impinge upon the internal walls of the gauging pole **18** in such a way that vapor is prevented from escaping from the tank **10** via the gauging pole **18**. In some applications, a single seal **48** can be used. However, in most applications, two spaced-apart seals **48** are required to adequately prevent vapor from escaping via the perforations **24** in the gauging pole **18**. This is clearly seen in FIG. 3. The float seals **48** are made from any suitable sealing material which is compatible with liquids which are to be stored within the tank **10**.

As shown in FIG. 4, a chain **50** or similar structure can be attached to the float **22** to facilitate its removal from the gauging pole **18** when samples are to be removed from the tank **10**.

Typically, the floating roof tank **10** of the invention will further comprise a suitable platform (not shown) attached to the upper edge of the side walls **14** to allow operations personnel access to the top of the gauging pole **18**.

In operation, the floating roof tank **10** of the invention can be partially filled with a volatile liquid. The floating roof **16** is buoyed upward by the buoyancy the pontoons **36** so that the floating roof **16** essentially rests at the top of the liquid. This minimizes any vapor space between the top of the liquid **38** and the bottom of the roof **16**. The periphery seals **40** prevent the escape of vapors from around the periphery **34** of the roof **16**.

The float **22** is disposed within the gauging pole **18**. The gauging pole seals **46** impinge upon the side walls of the gauging opening cylinder **42** to effectively prevent vapor

from escaping through the gauging opening **20** on the exterior of the gauging pole **18**.

The float **22** is buoyed upwards by its natural buoyancy. A portion of the float **22** is typically disposed below the liquid level **38**, with the remainder of the float **22** disposed above the liquid level **38**. The float **22**, in combination with the pair of spaced-apart float seals **48**, effectively prevent the escape of vapor from the inside of the tank **10** through the gauging pole **18**.

When operating personnel wish to take samples from the tank **10**, such personnel open the top cap **30** on the gauging pole **18** and remove the float **22** using the attached chain **50**. In this way, the operating personnel have access to the contents of the liquid within the gauging pole **18** which, because of the perforations **24** in the gauging pole **18**, is representative of the liquid in the tank **10** as a whole. The operating personnel extract the required samples and then replace the float **22** within the gauging pole **18** using the chain **50**.

Having thus described the invention, it should be apparent that numerous structural modifications and adaptations may be resorted to without departing from the scope and fair meaning of the instant invention as set forth hereinabove and as described hereinbelow by the claims.

What is claimed is:

1. A floating roof tank comprising:
  - (a) a bottom wall;
  - (b) substantially vertical side walls attached to the bottom wall, the side walls defining a top opening;
  - (c) a roof disposed within the side walls, the roof having a central portion, peripheral edges and a gauging opening and being shaped and dimensioned to substantially conform to the top opening, the roof being adapted to float on liquid disposed within the tank and having seals disposed at the peripheral edges to substantially seal vapor within the tank;
  - (d) a hollow gauging pole disposed vertically within the tank and protruding through the gauging opening in the roof, the gauging pole having side walls with an exterior side and an interior side, the gauging pole side walls being perforated to allow liquid within the tank to flow into the gauging pole and having external seals adapted to seal the exterior side of the gauging pole side walls to the tank roof so as to prevent vapor within the tank from escaping through the gauging opening on the exterior side of the gauging pole side walls; and
  - (e) an internal float disposed within the gauging pole adapted to float on liquid disposed within the tank, the float having a pair of spaced apart wiper seals adapted to seal the float to the interior side of the gauging pole side walls so as to prevent the escape of vapor from the tank along the interior side of the gauging pole side walls.
